UNITED STATES PATENT OFFICE.

MAX TETZLAFF, OF LANKWITZ, GERMANY.

PIN-TICKET.

1,220,907.

Specification of Letters Patent. Patented Mar. 27, 1917.

Application filed April 7, 1913. Serial No. 759,522.

To all whom it may concern:

Be it known that I, MAX TETZLAFF, a subject of the German Emperor, residing at Lankwitz, Germany, have invented certain 5 new and useful Improvements in and Relating to Pin-Tickets, of which the following is a specification.

This invention relates to a novel fastening clip for tickets and is especially applicable 10 for fastening price and like tickets to pieces of cloth or similar draperies or fabrics.

The object of the present invention is to provide a simple, cheap and safe fastener for such show tickets. This object is obtained 15 by forming the wire fastener with needle ends which project through and laterally from the show ticket and are bent above the top edge of the ticket into a loop which may in turn be bent over the edge of the 20 article to be ticketed. The needle ends may then be passed through the material or article to be ticketed and the loop and needles are bent in toward one another to lie in a plane parallel to the ticket and at the side 25 of the cloth or article remote from the ticket. The loop may be conveniently bent at an intermediate point to form a gage for positioning the ticket, the bent portion being caused to rest against the edge of the cloth or like 30 article. In this way a pleasant uniformity in the placing of the ticket is simply and efficaciously obtained. At a point intermediate the sharpened or needle ends, a return fold may be formed in the wire so as to provide 35 a clamp adapted to engage the ticket on opposite sides.

The ease of manufacture of the fastener according to the present invention is naturally more or less in direct proportion to 40 its simplicity of design. The number of the return bends and loop portions which project above the ticket may be increased as desired. The gage and clamping bend form protectors for the needle ends and thereby prevent injury to the fingers of the operator 45 or window dresser. The card or ticket may be readily removed from the article by bending back the projecting loop without touching the needle ends and thereby danger or

injury to the fingers is still further diminished. 50

The invention is illustrated in the accompanying drawings by way of example.

In these drawings:

Figure 1 is a front view of a ticket clip 55 according to the present invention.

Fig. 2 is a rear view of the same.

Fig. 3 is a side view of the clip.

Fig. 4 is a rear view of the ticket clip secured to a piece of fabric. 60

As shown, the ticket clip is formed of a single piece of wire *c* having sharpened ends *b* and forming a plurality of looped portions shaped so as to project above the top edge of the ticket *a*. These looped portions are 65 bent as at *c'* at intermediate points so as to form a gage for positioning the ticket, and the return folded portions *f*, *g* are located at the sides of said looped portions outside of the legs of the loop and are adapted to 70 engage the ticket on opposite sides, while the lateral projecting portions *b* terminate in needle ends and are adapted to pass through the card or ticket from front to the rear or, as shown in Fig. 4, also through the 75 cloth, while the bend *c'* rests against the edge. The operator may then pass the needle ends *b* upwardly and press the same against the ticket and the fabric whereafter he presses the protecting loops *c'* downwardly on top 80 of the needle ends *b* as shown in Fig. 4.

In use, the clip may be fastened by one hand if the operator presses the sharpened ends *b*, upward with the thumb of the right hand and then presses down the protecting 85 loop *c'*, with the fingers.

For removing the ticket the protecting ends *c'*, are bent upward whereupon the ticket may be withdrawn from the material by a downward movement which pulls the 90 needle ends *b*, back through the material.

I claim:

A ticket clip comprising a single piece of wire having sharpened ends thereon, said wire having a plurality of looped portions 95 adapted to project above the top edge of the ticket, said looped portions being bent at intermediate points to form a gage for po-

sitioning the ticket, return folded portions located at the sides of said looped portions and adapted to engage the ticket on opposite sides and lateral projecting portions terminating in the sharpened ends, said projecting portions being adapted to pass through and project laterally from the rear side of the ticket.

In testimony whereof I have signed my name to this specification in the presence of 10 two subscribing witnesses.

MAX TETZLAFF.
